UNITED STATES PATENT OFFICE

2,442,946

APPARATUS FOR PRODUCING SHEET MATERIAL

Richard E. Barton, Maplewood, N. J., assignor to
Rope-Soles, Inc., New York, N. Y., a corpora-
tion of Delaware

Application August 8, 1944, Serial No. 548,615

6 Claims. (Cl. 242—7)

1

This invention relates to a machine or apparatus for use in producing sheet material formed of strips disposed in abutting side by side relation and adhesively secured to each other in said relation to form the sheet.

As the sheet material of the present invention is intended primarily for use in the manufacture of outsoles for shoes, said outsoles being of the type known as rope soles, the strips which are secured to each other in side by side relation in the sheet are formed of braided rope or similar material. Rope soles and the sheet material for producing the same are shown and described in the United States patent to Wilpan No. 2,315,759, issued April 6, 1943. The present invention has for its primary objects the provision of an efficient and commercially practical method of producing the sheet material of the construction disclosed in said patent, that is sheet material from which rope soles can be produced by die-stamping or otherwise cutting the rope soles therefrom.

The above and other objects, features, and advantages of the invention will be fully understood from the following description considered in connection with the accompanying illustrative drawings.

In the drawings:

Fig. 1 is a side view of a machine or apparatus embodying the present invention and is also illustrative of a step in the method of the present invention;

Fig. 2 is a fragmentary perspective view of sheet material produced in accordance with the present invention;

Fig. 3 is a sectional view on the line 3—3 of Fig. 1;

Fig. 4 is a sectional view on the line 4—4 of Fig. 3;

Fig. 5 is a sectional view on the line 5—5 of Fig. 3;

Fig. 6 is a sectional view on the line 6—6 of Fig. 3;

Fig. 7 is a plan view of the parts illustrated in Fig. 5;

Fig. 8 is a fragmentary perspective view of part of the apparatus;

Fig. 9 is a sectional view on the line 9—9 of Fig. 1;

Fig. 10 is a plan sectional view on the line 10—10 of Fig. 9;

Fig. 11 is a side view of part of the apparatus and illustrates the feed of the strip material;

Fig. 12 is a top plan view of strip-winding apparatus, showing a modification, with portions broken away for the purposes of illustration;

2

Fig. 13 is a detail view, on a larger scale, of a spring-operated roller in the modification illustrated in Fig. 12.

In accordance with the method of the present invention, the sheet material S, which is similar to the sheet material described and illustrated in the above mentioned patent and comprises a plurality of latex coated or impregnated strips 10 of braided rope or similar material, is produced by winding a length of said material, slitting or cutting through said winding along one or more lines, so that the winding can be flattened or formed into a sheet from which the outsole blanks B can be die-stamped or cut as indicated in dotted lines in Fig. 2. The winding is indicated at W in Fig. 1 and, as hereinbefore more particularly described, is preferably formed on the hollow cylindrical drum 12 of the apparatus embodying the present invention. As illustrated in Figs. 1 and 3 said drum 12 is provided with one or more slots, here shown as two diametrical opposed slots 14, extending longitudinally of the drum, so that the winding W can be slit accordingly to facilitate the removal of the winding from the drum and to allow the winding to be flattened into one or more sheets S.

Thus, in accordance with the method of the present invention, a length of the strip material is first coated or impregnated with latex or any other suitable adhesive (latex being preferred); then the strip material is formed into a winding in which the adjacent turns are adhesively secured in face to face relation; then said winding is cut and formed into one or more sheets in which the strips are disposed in side by side relation. During the winding of the strip material, pressure is applied to the material as it is wound around the drum so that the successive turns of the material in the winding are pressed against each other in face to face abutting relation and are adhered to each other in said relation by the latex or other adhesive with which the strip material is coated or impregnated. The strip material is wound, as hereinafter more particularly described, so that the thickness of the sheet is determined by the width of the strip material.

As illustrated in Fig. 3, the braided rope 10A (or other strip material) corresponding to the strips 10 of sheet S (Fig. 2), is supplied to the drum 12 tangentially thereof, the leading end of said length of rope being secured in any suitable way to the drum at the lower end thereof, as by tying or otherwise fastening said leading end of the rope to a pin or lug 16 fixed to the drum near the lower end thereof. The rope 10A is coated

or impregnated with a suitable adhesive preferably latex, and while the rope is being wound around the drum in helical formation thereon, pressure is applied to the rope as it is laid in position around the drum, as the drum rotates, whereby the successive turns of the rope winding are adhesively secured to each other in abutting face to face relation. It will be understood that the latex or other adhesive coated or impregnated rope 10A is wound on the drum while the latex or adhesive is in non-dried, that is, in moist or tacky condition, and that the winding formed from said rope is removed from the drum before the adhesive sets sufficiently to cause the winding to adhere to the drum. If desired, the surface of the drum can be coated with a substance, for example, chalk, to prevent the strip material from adhering to the drum.

The rotary drum 12, which is hollow as illustrated, can be of any suitable construction and as here shown is mounted in vertical position for rotation on a base 18 of any suitable construction. The bottom 20 of the drum is provided with a central bearing-trunnion 22 which is journaled for rotation in the bearing 24 fixed to base 18. The drum is further supported for rotation on base 18 by a plurality of circumferentially spaced casters or wheels 26 mounted on base 18 and engaged by a flat circular plate 28 fixed to the bottom 20 of the drum. Said bottom 20 of the drum is provided with a gear 30 which meshes with and is driven by a gear 32 rotated in any suitable way as by an electric motor M through reduction gearing 34.

Provision is made for guiding the length of rope or other narrow strip material 10A to the drum, for laying said material in successive turns around said drum along the length thereof, while the drum rotates, and for pressing said turns against each other in the direction of the length of the drum. The means provided for these purposes comprises a collar member 36 which surrounds the drum and which is movable longitudinally of said drum by the material as the latter is wound around the drum in successive turns longitudinally of the drum as just stated. Said collar member 36 is held against turning in the direction of winding rotation of the drum, that is in the direction of arrow A, by a pin 38 which engages a rod 40 which is fixed to base 18 in upstanding relation thereto. It will be understood that as collar 36 is moved longitudinally of drum 12, pin 38 slidably engages rod 40 and moves longitudinally thereof. Collar member 36 is preferably formed of channel iron stock and, as shown, the inner peripheral edges of the opposed side walls 42 and 44 thereof lie close to the outer peripheral surface of the drum with a slight clearance. A flanged roller 46 is mounted for rotation in collar member 36 at the point where the strip material 10A is supplied to the drum. Said roller 46 is mounted for rotation on the shank 48 of a shouldered bolt which is fastened by a nut 50 to the end wall 52 of collar member 36. Preferably as here shown, an anti-friction member such as a roller 54 is provided near the flanged roller 46.

As illustrated in Fig. 11, the strip material passes over said anti-friction roller 54, into the opening 56 in the side wall 42 and under the flanged roller 46 through the opening 57 in the other side wall 44 of collar member 36. A plurality of circumferentially spaced rollers 58 are carried by collar member 36 and are mounted for rotation therein on the shanks 60 of companion

shoulder bolts which are secured to the end wall 52 of the collar member by nuts 62. As shown, rollers 46 and 58 project through openings in side wall 44 of the collar member and engage the strip material 10A for applying pressure thereto, in a direction extending longitudinally of the drum for pressing the successive turns of the strip material against each other in abutting face to face relation while the material is being wound on the drum. The pressure thus applied to the strip material by the rollers 46 and 58 is derived from the weight of collar member 36 and said rollers which are mounted thereon. It will be understood, however, that if desired additional pressure can be obtained by means of weights fixed to or suspended from collar member 36 at circumferentially spaced points, but ordinarily sufficient pressure is provided by the weight of collar member 36 the rollers mounted thereon.

As shown, the apparatus is also provided with means for applying pressure to the strip material 10A edgewise thereof and radially inwardly toward the drum during the winding of said strip material. For this purpose there are provided the rollers 64 which are disposed at diametrically opposite points of collar member 36 and correspondingly diametrically opposite points of drum 12. Rollers 64 are mounted in position by means of brackets 66 which are fixed to the end wall 52 of the collar member (Fig. 5). Each roller 62 is mounted for rotation on the shank 68 of a shouldered bolt which is secured to the companion bracket 66 by a nut 70. Bracket 66 is provided with a slot 72 in which the narrower part 74 of the bolt shank is adjustable whereby to provide for the adjustment of roller 64 in relation to the confronting edge of the strip material 10A. It will be understood that each roller 64 is positioned in such spaced relation to the outer peripheral surface of the drum 12 as to exert pressure on the edge of the strip material while the drum rotates for forming the winding thereon. It will be noted that the strip material 10A of the winding W is of greater width than thickness and that said strip material is disposed with the narrower dimension or edge thereof against the drum, the wider dimension or face of the strip material lying in a plane transverse to the drum axis. Accordingly, after the winding is cut and removed from the drum and flattened into the sheet S, the strips 10 formed from the strip material 10A are disposed in the sheet in such relation that the thickness of the sheet corresponds to the wider dimension or face of the strip material. It will be understood, however, that the strip material may be differently dimensioned as to its width and thickness as well as in respect to its structure and cross sectional shape or peripheral contour. Although the drum 60 may be of any suitable diameter and of any suitable length, it may be stated by way of illustration, but without limitation, that in apparatus constructed and operated in accordance with the present invention and in the practice thereof, drums 5 ft. in diameter and 5½ ft. long have been used with great practical advantage. When the windings formed on such drums are removed therefrom, following the slitting of the winding at the slots 14, that is along lines extending parallel to the axis of the drum and transversely of the abutting face of the turns of the winding, two sheets or mats of material of the construction illustrated in Fig. 2 are produced, each sheet having a length of about 8 ft. measured in the direction of the length of the strips 10 and a

width corresponding to the extent of the winding longitudinally of the drum, the maximum width of said sheet on a drum of the above mentioned length about 5 ft. being of course equal to about the length of the drum when as in actual practice, the winding extends for about the full length of the drum. Accordingly, the sheet material is produced in the form of comparative large mats or sheets from which a large number of rope sole blanks can be formed by die stamping or cutting the same as described above. It will be observed that as the drum is of large diameter in relation to the thickness of the strip material, the pitch of the helical winding is low whereby the sheet or sheets produced from the winding are substantially of rectangular outline.

Instead of winding the strip material 10A helically about a drum with the successive turns of the winding disposed longitudinally of the drum, which is the preferred mode of winding in practicing this invention, the strip material 10A can be wound spirally to form a winding W1 as illustrated in Fig. 12. Thus as here shown, the strip material 10A is wound around a circular form or short drum 12A on a flat supporting plate 74. After the winding W1 is formed it is slit along the radially extending lines as indicated at 78 and after the slit winding is removed from the drum 12A, said winding is formed into a flat mat or sheet by spreading the cut ends of the slit winding away from each other until the strips are disposed in rectilinear relation thus forming a sheet similar to the sheet S illustrated in Fig. 2. It will be noted that in this case the wider dimension of the face or faces of the strips extend axially of the drum instead of at right angles to the drum as in the case of the winding formed on the drum 10. A series of circumferentially spaced spring-pressed rollers 76 can be provided in forming the winding W1 for pressing the turns of the winding against each other while the winding is being formed. Further it will be understood that the drum 12A, which is preferably rotatable is of a diameter sufficiently large to provide the winding W1 with a large radius of curvature so that after the winding is slit it can be bent into rectilinear form without distortion or relative displacement of the strips in the resulting sheet. Drum 12A can be rotated by an electric motor or in any suitable way, and if desired a plurality of said drums can be arranged in tandem or end to end, together with companion rollers 76, so that a plurality of windings W1 can be produced simultaneously. As illustrated in Figs. 12 and 13, plate 74 is provided with a plurality of longitudinal slots 80 in which the pin bearings 82 on which rollers 76 are rotatable are movable by the companion tension springs 84 as the winding expands. One end of each spring 84 is fixed to a companion pin 82 and the opposite end of the spring is fixed to plate 74 at the adjacent end of the companion slot 80.

It will be understood that various changes may be made in the apparatus and method without departing from the underlying idea of the invention within the scope of the appended claims.

Having thus described my invention, what I claim and desire to secure by Letters Patent is:

1. Apparatus of the character described comprising means for forming a winding from a length of strip material with the turns of the winding in abutting relation, said means comprising a vertically positioned drum mounted for rotation about its vertical axis, and pressure-applying means surrounding said drum and posi-

tioned horizontally to press the successive turns of the winding against each other in said relation, said pressure applying means being movable axially of the drum, against the action of gravity, by the engagement therewith of the strip material as the latter is being wound around the drum.

2. Apparatus of the character described comprising a rotary winding-drum for winding a strip of material into a winding having its turns disposed in side by side relation longitudinally of the drum, and means for pressing the successive turns of the winding against each other in the direction of the length of the drum, said pressure-applying means comprising a member surrounding said drum and movable longitudinally thereof and a plurality of rollers carried by said member and engageable with portions of the strip in pressure-applying relation thereto.

3. Apparatus of the character described comprising a rotary winding-drum for winding a strip of material into a winding having its turns disposed in side by side relation longitudinally of the drum, and means for pressing the successive turns of the winding against each other in the direction of the length of the drum, said pressure-applying means comprising a member surrounding said drum and movable longitudinally thereof and a plurality of rollers carried by said member and engageable with portions of the strip in pressure-applying relation thereto, and means for preventing turning movement of said longitudinally movable member in the direction of strip-winding rotation of said drum.

4. Apparatus of the character described comprising a rotary winding-drum, a collar surrounding said drum and mounted for movement longitudinally of the drum while held against turning movement in the direction of wind of the drum, means carried by said collar and movable therewith for guiding a length of narrow strip material to said drum and for laying said material in successive turns around said drum along the length thereof, and means carried by said collar for pressing said turns against each other in the direction of the length of the drum.

5. Apparatus of the character described comprising a rotary winding-drum, a collar surrounding said drum and mounted for movement longitudinally of the drum while held against turning movement in the direction of wind of the drum, means carried by said collar and movable therewith for guiding a length of narrow strip material to said drum and for laying said material in successive turns around said drum along the length thereof, and roller means carried by said collar for applying pressure to the material as it is wound on the drum, said roller means acting on said material in the direction of the length of the drum for pressing the turns against each other.

6. Apparatus of the character described comprising a rotary drum disposed in vertical position and rotatable about a vertical axis, means movable longitudinally of said drum for guiding a length of narrow strip material to said drum and for laying said material in successive turns around said drum along the length thereof, means surrounding said drum and acting longitudinally of said drum for pressing said turns against each other in the direction of the length of the drum, said pressing means being movable axially of the drum, against the action of gravity, by the engagement therewith of the strip material as the latter is being wound around the drum, and means

operable while said material is wound on the drum for exerting pressure on the edge of said material on the drum in a direction radially inwardly of said drum.

RICHARD E. BARTON.
